US00D816000S

(12) **United States Design Patent** (10) Patent No.: **US D816,000 S**
(45) Date of Patent: **** Apr. 24, 2018**

(54) **REMOTE CONTROL FOR DRONES**

(71) Applicant: **PARROT DRONES**, Paris (FR)

(72) Inventor: **Edouard Simoens**, Paris (FR)

(**) Term: **15 Years**

(21) Appl. No.: **35/501,462**

(22) Filed: **Jun. 13, 2016**

(80) **Hague Agreement Data**

Int. Filing Date: **Jun. 13, 2016**

Int. Reg. No.: **DM/092093**

Int. Reg. Date: **Jun. 13, 2016**

Int. Reg. Pub. Date: **Sep. 2, 2016**

(30) **Foreign Application Priority Data**

May 17, 2016 (EM) 003135813

(57) **CLAIM**

Ornamental design for a remote control for drones, as shown and described.

DESCRIPTION

1. Remote control for drones

1.1 : Front

1.2 : Back

1.3 : Left

1.4 : Right

1.5 : Top

1.6 : Bottom

1.7 : Perspective
